UNITED STATES PATENT OFFICE

WALTER L. PIPES, OF ELIZABETH, NEW JERSEY, ASSIGNOR TO THE SHOE HARDWARE COMPANY, OF NEW HAVEN, CONNECTICUT, A CORPORATION OF CONNECTICUT

SEPARABLE FASTENER

Application filed October 23, 1931. Serial No. 570,526.

This invention relates to completely separable fasteners of the type wherein a series of interlocking members are disposed on the edges of a stringer and arranged to be engaged and disengaged by the actuation of a slider.

Fasteners constructed of two series of interlocking members adapted to be engaged and disengaged by the operation of a slider are commonly referred to as slider fasteners. It is desirable that this type of fastener be constructed so that the stringers carrying the two series of elements be completely separated. One instance in which such a construction is required is in the manufacture of such articles of apparel as sport shirts or coats wherein it is desired to incorporate a fastener construction enabling the article to be put on in the manner of an ordinary shirt rather than slipped on over the head in the manner of a slipover sweater.

Devices have been suggested to enable slider fasteners to be completely separated, yet their construction has heretofore involved a considerable number of parts with a concomitant increase in manufacturing costs. This invention relates to the construction of a separable slider fastener with a minimum number of parts. This result is achieved in part by so arranging the novel separable connection so that the slider and the interlocking members may coact therewith to enable certain of the interlocking members to be utilized to act as a means for registering the two series of interlocking members in proper alignment preparatory to engaging them and fastening the stringers together. By the utilization of certain of the interlocking members as a stop means it is apparent that the number of parts of the separable connection itself may be reduced.

The invention involves an extremely simple construction and is simple and economical in manufacture, and results in a separable fastener which may be quickly and easily operated. Other advantages of the invention will more clearly appear when reference is had to the following specification and drawing.

In the drawing:

Fig. 1 is a plan view of a slider fastener constructed to embody the principles of this invention, parts of the slider being cut away to show the novel principle of operation. 55

Fig. 2 represents the slider fastener with the slider advanced a considerable distance over the interlocking member so as to engage the same.

Fig. 3 is a view of the slider fastener of 60 this invention with the two stringers completely separated.

Fig. 4 is a sectional view taken along line 4-4 of Fig. 2.

Fig. 5 is a perspective view of one type of 65 separable connection adapted for use with this invention.

On stringers 1 and 2 provided with enlarged corded edges 5 and 6 are disposed a series of interlocking members 3 and 4. 70 These members are adapted to be engaged and disengaged by the operation of a slider 8 having a central channel 11 adapted to encompass the members in their interlocking position, and connected and diverging channels 9 and 10 through which the members 4 and 3 may pass upon movement of the slider and preparatory to their engagement or after their disengagement. On the slider is disposed a bail 12 on which is arranged operating member 13 enabling the actuation of the slider. 75 80

At one end of the stringer 1 is clamped a separable connection 7. This consists in a pair of substantially tubular elements 14 and 15 connected together in any suitable way such as by a connecting piece 16 which may be soldered thereto. Member 14 is clamped upon the corded edge 5 of the stringer 1 whereas member 15 is constructed of a slightly greater diameter so that the corded edge 6 of stringer 2 may be passed therethrough. The connecting member 7 is clamped on the bead 5 at a distance from the last interlocking member 3' of the series disposed on stringer 1 so that the member 3' is positioned slightly below the middle (measured from top to bottom) of the slider when the latter is abutted against the connecting member 7. In this position it will be seen that the mem- 90 95 100

ber 3' assumes a position entirely out of the channel 10 through which it is adapted to slide and sufficiently far in the channel 11 so that the interlocking members on the adjacent stringer 2 cannot be passed by it when the corded edge 6 is pulled down in the direction of the arrow in Fig. 1. The last interlocking member 4' on the stringer 2 thus abuts against the member 3' and prevents further movement of the stringer 2 and registers the two series of interlocking members in proper alignment for interengagement upon actuation of the slider. In operation the slider 8 is abutted against the separable connection 7 and the corded edge 6 of stringer 2 is inserted through the channel 9 and through the tubular member 15 of the separable connection. The cord 6 is pulled downwardly in the direction of the arrow as far as it will go so that the last interlocking member 4' of the series of members 4 abuts against the last interlocking member 3' of the series 3. The two cords are then held, as between the thumb and forefinger, and the operating member 13 of the slider grasped and pulled upwardly, thus engaging the interlocking members. In unfastening the device it is apparent that the slider 8 is brought down to abut again against the separable connection 7, at which time the cord 6 and stringer 2 may be withdrawn through member 15 and channels 11 and 9. In order to insure a firm grip upon the cord 6 to prevent it from being displaced laterally the separable connection may be constructed as illustrated in Fig. 5 with a barrel portion 18 designed to loosely encircle the corded edge of the tape. In this as well as the other embodiment of the invention the separable connection may be constructed of one piece, for example as shown in Fig. 5, and the corded edge 6' may be provided with a metal ferrule 17 for convenience of insertion.

By fixing the connection 7 upon the corded edge 5 of stringer 1 a predetermined distance as above described from the interlocking member 3', it is apparent that I have constructed a slider which utilizes the last two elements of each series as a means for registering the two series in proper relation or alignment for engagement, thus eliminating the necessity of special stop or guide members thus greatly simplifying the construction and commercial manufacture of a separable slider fastener.

Having thus described my invention, what I claim and desire to protect by Letters Patent is:

1. The combination with a separable fastener comprising interlocking elements secured to enlarged margins of opposed flexible stringers and a slider for operating the same, of a connecting member fixed to the enlarged margin of one stringer and loosely engaging the enlarged margin of the other stringer, said connecting member halting movement

of the slider in a predetermined position, the lowermost interlocking element on the stringer to which said connecting member is fixed being located at such a distance from the connecting member as to obstruct passage through the slider (when the latter is in contact with the connecting member) of the lowermost interlocking element on the other stringer and thereby permitting the interlocking elements on the two stringers to be engaged by movement of the slider from a position in contact with said connecting member, and said connecting member being adapted to prevent disengagement of the interlocking elements adjacent thereto after the slider has been moved to a position remote therefrom.

2. A separable fastener comprising a pair of stringers having opposed series of interlocking members, a slider having diverging channels movable along such stringers to engage and disengage said members, a separable connection comprising a pair of connected tubular elements one of which is fixed upon one of said stringers and the other adapted to permit the corded edge of the other stringer to be passed therethrough, the said connection being distanced from the last interlocking member of the stringer to which it is attached an amount determined so that the last interlocking member on the other stringer may abut against the last interlocking member on the first stringer when the slider is abutted against said connection.

3. A separable fastener comprising a pair of stringers having opposed series of interlocking members, a slider having diverging channels movable along such stringers to engage and disengage said members, a separable connection comprising a pair of connected tubular elements one of which is fixed upon one of said stringers and the other adapted to loosely encircle the corded edge of the other stringer and prevent lateral movement thereof, the said connection being distanced from the last interlocking member of the stringer to which it is attached an amount determined so that the last interlocking member on the other stringer may abut against the last interlocking member on the first stringer when the slider is abutted against said connection and thereby the interlocking members on the pair of stringers may be interlocked by movement of the slider from its position abutting said connection.

Signed at New York, county of New York, State of New York, this 22nd day of October, 1931.

WALTER L. PIPES.
